JOHN P. HORN, INVENTOR

BY

Geo. P. Kimmel

ATTORNEY.

UNITED STATES PATENT OFFICE.

JOHN P. HORN, OF LANCASTER, PENNSYLVANIA.

FURNITURE ATTACHMENT.

Application filed June 6, 1922. Serial No. 586,233.

To all whom it may concern:

Be it known that I, JOHN P. HORN, a citizen of the United States, residing at Lancaster, in the county of Lancaster and State 5 of Pennsylvania, have invented certain new and useful Improvements in Furniture Attachments, of which the following is a specification.

This invention relates to upholstered 10 furniture, and has for one of its objects to provide an insecticide holder supported in the framework of such devices to prevent insects from attacking the upholstering.

Another object of the invention is to provide 15 a device of this character which may be applied without material structural change to articles of upholstered furniture of various forms and sizes, and whose presence will not be apparent and does not require any 20 change of form of the furniture.

Another object of the invention is to provide 25 a device of this character whereby air currents are caused to pass through the insecticide holders by the compression and release 30 action of the spring supported seat, to carry the emanations from the insecticide substance into contact with the upholstering material every time a person occupies the 35 seat and rises therefrom.

With these and other objects in view the 40 invention consists in certain novel features of construction as hereinafter shown and described and then specifically pointed out in the claims, and in the drawings illustrative 45 of the preferred embodiment of the invention:

Figure 1 is a front elevation of a conventional upholstered arm chair with the seat frame partly in section, and the improved 40 insecticide holder supported therein.

Fig. 2 is a vertical section on the line 2—2 of Fig. 1.

Fig. 3 is a transverse section on the line 3—3 of Fig. 1.

Fig. 4 is a plan view, and—

Fig. 5 is a side elevation, of the insecticide holder.

Fig. 6 is a transverse section on the line 6—6 of Fig. 5.

The improved device may be installed in any form of upholstered furniture, but for the purpose of illustration is shown applied to the framework of a conventional arm

chair, in which 10 represents the seat frame, 55 11 the back frame, and 12 the arms.

The upholstered seat portion is represented conventionally at 13 and is supported by springs 14, in the usual manner.

Built into the framework are one or more receptacles for a container for an insecticide 60 compound, and for the purpose of illustration is shown formed by partition members 15 spaced from the side and back rails 10 of the seat frame and provided with numerous vent apertures 16.

Suitably supported within each of the receptacles is a holder for an insecticide, each holder consisting of a casing or frame having end members 17 connected by upper and lower side bars 18 and with the sides and 70 bottom of screen material represented at 19. The top portion of the holder is formed with an intermediate section 20, and detachable lateral portions 21, preferably of wood and provided with numerous vent apertures 22. 75

The detachable portions 21 provide means for the insertion and removal of the insecticide element which may be of any suitable substance or material, for instance red cedar chips charged with a suitable formaldehyde. 80

The weight of a person occupying the seat 13 will depress the latter and force air through the apertures in the holder, and then when the occupant of the chair rises, the reaction of the springs 14 will cause the upholstering and its padding to draw fresh air into the holder and cause the charged air in the holder to impregnate the upholstering material and thus protect it from the attacks 85 of insects.

A suction action is thus produced by the compression and expansion of the seat structure caused by the occupant sitting and rising, as will be obvious.

The receptacles for the insecticide contain- 95 ers being located entirely within the lines of the frame members, are not visible from the outside and do not therefore detract from the appearance of the furniture, and do not add materially to the expense or weight.

The improved attachment is simple in construction, can be arranged in any portion of the framework of upholstered furniture, and effectively prevent insects from attacking the fabric constituting the upholstering.

The preferred embodiment of the inven-

tion is disclosed in the drawings and set forth in the specification, but it will be understood that modifications within the scope of the claimed invention may be made in the construction without departing from the principle of the invention or sacrificing any of its advantages.

Having thus described the invention, what is claimed as new is:—

- 10 1. An article of furniture including a supporting framing and upholstered portions, said framing having a receptacle built therein, and a casing for an insecticide having foraminous walls and received in said receptacle.
- 15 2. An article of furniture including the seat framing having a receptacle built there-

in, a casing adapted to receive an insecticide and having foraminous walls and received in said receptacle.

20 3. An article of furniture including the seat framing and the spring supported seat, said framing having a receptacle built therein, a casing adapted to receive an insecticide and having foraminous walls and received in 25 said receptacle, whereby the depression of the seat will force air through the holder and in contact with the insecticide therein and the return of the seat to distended position will draw the charged air into contact with 30 the upholstering.

In testimony whereof, I affix my signature hereto.

JOHN P. HORN.
